MOBILE FOOD VENDING UNIT

Delmer James Hill, P.O. Box 6873,
Grosse Pointe Woods, Mich. 48236

Filed Feb. 5, 1968, Ser. No. 10,447

Term of patent 14 years

Int. Cl. D12—10

U.S. Cl. D14—3

FIGURE 1 is a side elevational view of a mobile food vending unit showing my design.

FIGURE 2 is an end elevational view.

FIGURE 3 is a cross-sectional view thereof taken on the line 3—3 of FIGURE 1.

FIGURE 4 is a perspective view of my invention in its in-transit configuration.

FIGURE 5 is a perspective view of my invention in a use configuration.

FIGURE 6 is a perspective view of my invention in another in-use configuration.

I claim:

The ornamental design for a mobile food vending unit, as shown and described.
